UNITED STATES PATENT OFFICE.

ORMSBY P. WILLIAMS, SR., OF SOUTHGATE, CALIFORNIA.

VENTILATING FOOT COVERING.

Application filed October 27, 1926. Serial No. 144,555.

My invention relates to foot coverings, and it has for its purpose the provision of a boot or shoe in which is incorporated means for creating a forced circulation of air into and out of the foot covering so that adequate ventilation of the foot is at all times effected.

It is also a purpose of my invention to provide a boot or shoe having foot ventilating means which is operable by the usual motion of the foot in walking to set up a constant influx of fresh air into the shoe and around the foot and an efflux of stagnant air from the shoe, whereby fresh air is at all times supplied to the foot.

I will describe only two forms of ventilating foot coverings embodying my invention, and will then point out the novel features thereof in claims.

In the drawings.

Figure 1 is a view showing partly in elevation and partly in longitudinal vertical section one form of ventilating foot covering embodying my invention;

Figure 2 is a horizontal sectional view taken on the line 2—2 of Figure 1;

Figure 3 is a view similar to Figure 1, showing another form of ventilating foot covering embodying my invention.

Similar reference characters refer to similar parts in each of the several views.

In Figures 1 and 2, I have shown a ventilating foot covering in the form of a shoe in which the heel 15 thereof is constructed to provide a cavity 16 cup shaped in form, with its upper side open and spanned by the inner sole 17 of the shoe. Within this cavity is what I term a pumping device which comprises in the present instance a body 18 and an enlarged disk shaped head 19, both of which are preferably in the form of rubber or any suitable resilient material, which is capable of being compressed under the weight of the heel as in walking and to expand to its normal position when relieved of pressure so that the head 19 will be reciprocated in the cavity to effect a pumping action.

The outer sole 20 of the shoe is formed with an air duct 21 having its forward end extending upwardly as indicated at 21^a and communicating with an opening 22 in the inner sole so that the forward end of the duct is placed in communication with the interior of the shoe. The point of communication is preferably beneath the toes of

the foot and between the arch portions of the toes of the foot so that air from within the shoe can be readily drawn into the duct. The rear end of the duct extends into the heel 15 and at this point is provided with a valve unit comprising a body 23 having a spring pressed ball valve 24 therein, which operates to check the passage of air from the cavity into the duct, but which opens to allow the passage of air from the duct into the cavity.

To permit discharge of air from the cavity to atmosphere, the heel 15 is provided with a suitable opening in which is located a second valve unit 25 of the same construction as the other valve unit and operating to check the passage of air inwardly to the cavity.

In operating, the pumping device being disposed directly beneath the heel of the foot is subjected to the pressure of the heel in walking and thereby intermittently compressed to effect a reciprocating movement of the head 19 within the cavity. During downward movement of the head the air within the cavity is placed under pressure, which operates to open the valve 25 and thus discharge the air to atmosphere. On the upward movement of the head a negative pressure is created within the cavity, which operates to open the valve 24 and thereby place the duct 21 in communication with the cavity. In view of this negative pressure air is drawn from the interior of the shoe through the duct and into the cavity, such air being ultimately discharged from the cavity through the valve 25 on the subsequent down stroke of the heel. In this manner air is constantly withdrawn from the interior of the shoe and discharged through the heel, thereby creating a circulation of fresh air through the interior of the shoe to properly ventilate the foot.

Referring now to Figure 3, I have here shown another form of ventilating foot covering in its adaptation to a boot. The foot portion of the boot is constructed in substantially the same manner as the shoe shown in Figure 1 in that the heel portion is provided with a cavity 16 in which the pumping device is located, and a duct 21 extends through the outer sole of the boot and is in communication at its forward end with the interior of the boot. Instead of discharging air from the cavity 16 through the heel as in the first form of my invention, the air is dis-

charged into a tube 26 which extends upwardly along the inner side of the back of the leg portion of the boot, with its discharge end at the top of the boot in order to insure 5 the proper discharge of air from the cavity during the normal use of the boot, that is to say, when the foot portion of the boot is submerged in water.

In both forms of my invention, the 10 silent body 18, 19, also functions as a cushion for the heel of the foot in walking thus providing the advantages of a rubber heel and in a superior manner.

Although I have herein shown and described only two forms of ventilating foot coverings embodying my invention, it is to be understood that various changes and modifications may be made therein without departing from the spirit of the invention, and 20 the spirit and scope of the appended claims.

I claim:

1. A shoe having a heel formed with a cavity opening upwardly and spanned by the inner sole, a resilient body movable in the 25 cavity by the heel of the foot in the act of walking to alternately create negative and positive air pressures in the cavity, a valved discharge port in the heel communicating with the cavity through which air from the 30 cavity is discharged to atmosphere when a positive air pressure is created in the cavity, and a valved duct leading from the cavity to the interior of the shoe through which air from the shoe is drawn into the cavity when 35 a negative pressure is created in the cavity.

2. A shoe having a heel cavity, a duct extending from the cavity to the interior of the shoe, a valve in the duct for permitting air to be withdrawn from the interior of the shoe 40 into the cavity, a second valve in the heel allowing air to be discharged from the cavity, and means in the cavity operable by the foot for creating positive and negative

air pressures alternately in the cavity which through the coaction of the valves causes circulation of fresh air through the interior of 45 the shoe.

3. A foot covering having a heel formed with a cavity opening upwardly, a resilient body in the cavity, having an enlarged head 50 spanning the open end of the cavity to provide an annular passage beneath the head and between the body and wall of the cavity, said head normally elevated but adapted to be depressed in response to the weight of the 55 heel portion of the foot imposed on the head during walking, so as to alternately increase and decrease the pressure of air in the said passage, a valved discharge port through which air is discharged from the passage to 60 atmosphere when the pressure is increased in the passage, and a valved inlet duct communicating with the passage and the interior of the shoe, through which air from the shoe is drawn into said passage when the pressure of air in the latter is decreased.

4. A foot covering having a heel formed with a cavity opening upwardly, a resilient body in the cavity, having an enlarged head 70 spanning the open end of the cavity to provide a continuous passage surrounding the body beneath the head, said head normally elevated but adapted to be depressed in response to the weight of the heel portion of the foot imposed on the head during walking, so as to alternately increase and decrease the pressure of air in the said passage, a valved discharge port through which air is discharged from the passage to atmosphere 75 when the pressure is increased in the passage, and a valved inlet duct communicating with the passage and the interior of the shoe, through which air from the shoe is drawn into said passage when the pressure of air in the latter is decreased.
